UNITED STATES PATENT OFFICE.

HOWARD B. SHERMAN, OF BATTLE CREEK, MICHIGAN.

FEED-REEL.

1,277,762.

Specification of Letters Patent.

Patented Sept. 3, 1918.

Application filed August 8, 1917. Serial No. 185,081.

To all whom it may concern:

Be it known that I, HOWARD B. SHERMAN, a citizen of the United States, residing at Battle Creek, in the county of Calhoun and 5 State of Michigan, have invented certain new and useful Improvements in Feed-Reels; and I hereby declare that the following is a full, clear, and exact description thereof, reference being had to the accompanying drawings, which form part of this 10 specification.

This invention is a novel feed reel or machine for supporting a coil of wire or metal strip or ribbon while the same is being fed 15 to a machine, such, for instance, as a stamping press, operating upon such stock.

The objects of the present invention are to produce a feed reel capable of properly supporting coils of different diameters and 20 of different widths; which will be adjustable so that the center of the coil can be located to suit the machine to which the stock is to be fed; which will enable the coil to be readily revolved when in position; which can 25 properly support coils of different internal diameters and different widths or thicknesses; and in which the coil can be readily and quickly positioned in the reel by one operator without assistance from others.

30 My invention provides a reel having all these desirable features, and other minor novel features which enhance its utility, and will be readily appreciated by those skilled in the art.

35 I will explain the invention with reference to the accompanying drawings which illustrate practical embodiments thereof; but I do not consider the invention restricted to the specific forms or constructions of parts 40 shown in the drawings, and have set forth in the claims the essentials of the invention and novel features and combinations of parts for which protection is desired.

In said drawings:

45 Figure 1 is a side elevation of a feed reel embodying the invention.

Fig. 2 is an end elevation thereof.

Fig. 3 is a detail sectional view thereof.

40 Fig. 4 is a side elevation of a modified form of the invention.

Fig. 5 is an end elevation of Fig. 4.

Referring to Figs. 1 to 3 the rotatable coil support preferably comprises opposite rotatable and relatively adjustable members, 55 which are shown as composed of hubs 1 provided with radiating arms 1^a on which

are mounted adjustable collars 1^b having inwardly projecting horns 1^c. These collars may be secured by set screws 1^d or other suitable means. The hubs 1 of the members are 60 suitably mounted upon the inner ends of the stub-shafts 2 so that they may be easily rotated on said shafts, but preferably not capable of longitudinal movement thereon.

These shafts 2 may be journaled in any 65 suitable bearings and are preferably longitudinally adjustable in their bearings, and may slide therein, or they may be provided with threaded portions 2^a which engage internally threaded sleeves 3^a on the upper 70 ends of standards 3; which standards are mounted in guides 4^a on the side members 4 of the frame of the machine. The standards 3 are preferably made vertically adjustable on the frame and may be secured 75 when adjusted by set bolts 4^b or other convenient means. The frame side members 4 may be rigidly united by suitable cross pieces as indicated in the drawings.

The standards 3 should be adjusted so 80 that the shafts 2 and reel members 1 are in axial alinement. The shafts 2 may be independently adjusted by sliding or turning them in their bearings 3^a, and may be provided with suitable means, as hand wheels 85 2^c, by which they may be readily rotated or adjusted. When properly adjusted the shafts may be locked by set-screws 3^e tapped through the sleeves 3^a.

As the coils vary in internal diameter the 90 horns 1^c are adjustable radially of the spiders to suit the internal diameter of the coil to be supported on the reel.

The horns 1^c are preferably relatively short so that the movable spiders will only 95 have to be moved a minimum distance when placing a fresh coil on the reel.

Below the reel members 1 is a coil elevator 5, which is preferably Y-shaped and is adapted to support a coil in a vertical position intermediate the members 1; when in normal lowered position elevator 5 would support the coil eccentric to, or with its axis below the axis of, the members. This elevator 5 may have ribs 5^a on its opposite arms 100 to steady the coil and prevent it rolling off the support.

The elevator 5 is vertically movable and may be guided in any suitable manner; as shown the shank 5^b of the support passes 110 through a guide opening 4^c in a cross bar 4^d of the frame; and the lower end of this

shank is adjustably pivotally connected by a bolt 5^c to the inner end of a treadle lever 6 pivoted at 6^a on the frame. By depressing the outer end of this treadle the elevator will 5 be raised, and thereby the coil resting thereon can be elevated until it is axially alined with the members 1.

To facilitate the placing of a coil upon the elevator 5, in the machine shown in Fig. 10 1, an inclined way or plane 7 may be used; the upper end of said way is provided with a cross bar 7^a adapted to engage lugs 4^e on the ends of the side members 1, (see Fig. 1) and to the lower portion of this plane is 15 pivoted a hook 7^b which may be engaged with the adjacent end of the frame, as indicated in Fig. 1, so as to prevent the lower end of the plane tilting upward when a coil is being rolled over the upper end thereof 20 onto the elevator 5.

The horns 1^c should be first adjusted on the reel members to suit the internal diameter of the coil to be supported thereby. Then shafts 2 are adjusted to set the members 25 the proper distance apart to receive a coil between them. Then one of these members (say the left hand member Fig. 2) is backed away to permit a coil to be entered between the members; then a coil is 30 rolled up the inclined way 7 and onto the elevator 5 while the latter is in its lowered position, the coil then resting upon the elevator intermediate the members, as indicated in dotted lines in Fig. 1. Then the 35 operator by depressing treadle 6 raises the coil until it is disposed axially between the members, and while holding the coil so elevated he moves the left hand member back to position to cause the horns to meet and 40 support the coil; then he releases the treadle and the elevator drops leaving the coil suspended on the horns and properly centered between the members.

I preferably make both reel members 45 adjustable as the coils of wire or stock vary in width for different characters of work, and to enable any of such coils to be properly centered by elevator 5 between the members it is desirable to have both adjustable. 50 Usually where feed reels are used a number of coils of same diameter and size are used successively, and therefore frequent adjustment of both reel members is not necessary.

55 If it is desired to supply the coils from the opposite end of the machine the inclined way 7 can be readily detached and attached to that end of the machine. By having the elevator 5 bifurcated or provided 60 with opposite ribs 5^a the coils can be more easily registered and centered from front to back and in line with the spiders.

After a coil is used up, the members are 65 separated by moving say the left hand reel member a distance sufficient to permit the

entrance of a new coil between the horns 1^c; then a new coil is run up the inclined plane and onto the elevator 5 and raised to position between and axially of the members 1 and the movable member returned 70 to position so as to support the coil upon the horns as above described.

The elevator 5 may be adjustably connected to the treadle lever 6 in any suitable manner (being shown as provided with a 75 plurality of holes 5^d to engage the bolt 5^c) so that the distance the coil has to be elevated by depressing the treadle 6 will be small; the bolt 5^c may be engaged with an upper hole 5^d in the shank of the elevator 80 when coils of large diameter are used, and be engaged with a lower hole in the shank when coils of smaller diameter are used.

In the construction shown in Figs. 4 and 5 the spiders 1 are rotatably mounted on 85 stub-shafts 2^a attached to standards 4^e on the side frames 4. One of these standards, as the left hand one in Fig. 5, may be made adjustable toward or from the other standard and it may be operated by means of a 90 threaded shaft 4^f, or other suitable means. The elevator 5 is operated by treadle lever 6 as above explained. Instead of the detachable inclined plane or way, shown in Fig. 1, the side frames may be extended at one 95 end as shown at 4^b in Fig. 4, and connected by rods or rollers 4^g forming an inclined way up and over which the coil may be rolled onto the elevator 5.

The coils are positioned between the reel 100 members shown in Figs. 4 and 5 substantially as above explained, as will be readily understood.

While the reel members are shown as provided with six arms, the number of arms 105 may be varied; and as stated I do not consider the invention restricted in its broader aspect to the specific forms or construction of parts shown in the drawings.

What I claim is:

1. In a feed reel for coils of wire, the combination of opposite supports, rotatable coil engaging members mounted on said supports, means for adjusting the members toward or from each other to engage and support a coil between them, and a coil elevator below said members intermediate the supports. 115

2. In a feed reel for coils of wire, the combination of opposite supports, rotatable coil engaging members mounted on said supports, means for adjusting the members toward or from each other to engage and support a coil between them, a coil elevator below said members intermediate the supports 120 and means for directing a coil onto said elevator.

3. In a feed reel for coils of wire, the combination of opposite supports, rotatable coil engaging members mounted on said sup- 130

- ports, means for adjusting the members toward or from each other to engage and support a coil between them, radially adjustable coil engaging devices on said members, a 5 coil elevator below said members intermediate the supports, and means for directing a coil onto said elevator.
4. In a feed reel adapted to receive and support a coil while the same is unwound, 10 the combination of opposite rotatable members adapted to receive and support a coil between them, adjustable means on said members for engaging and centering such coil, and an elevator below and between the 15 members for raising a coil into position to be engaged and supported by said members.
5. In a feed reel adapted to receive and support a coil while the same is unwound, means for engaging and supporting a coil, 20 an elevator for raising a coil relative to and into position to be engaged by the supporting means, and a way up which the coil to be supported may be rolled onto the elevator.
6. In a feed reel adapted to receive and 25 support a coil while the same is unwound, the combination of opposite rotatable members adapted to support a coil, adjustable means on said members for engaging said coil and centering it thereon, and an ele- 30 vator below and between said members adapted to lift a coil into position to be engaged by said members, with an inclined way up which said coil may be rolled onto said elevator.
7. In a feed reel adapted to receive and support a coil while the same is unwound, 35 the combination of relatively adjustable rotatable members, adjustable means on said
- members for centering and supporting a coil thereon, vertically adjustable supports 40 for said members, and a coil elevator below the members and between the supports.
8. A feed reel adapted to receive and support a coil while the same is unwound, comprising independent relatively adjustable ro- 45 tatable members, adjustable supports for said members, adjustable devices on said members for supporting and centering a coil thereon, a coil elevator between said ad- justable supports adapted to receive a coil 50 and elevate it between said members, and means by which a coil may be directed onto said elevator.
9. A feed reel adapted to receive and sup- 55 port a coil while the same is unwound, comprising opposite relatively adjustable rotatable members, adjustable supports for said members, radially adjustable devices on said members for supporting and centering a coil therebetween, a coil elevator below and be- 60 tween said members adapted to receive a coil and elevate it into position to be en- gaged by said devices; and an inclined way up which a coil may be rolled onto said ele- 65 vator.
10. In a feed reel adapted to receive and support a coil while the same is unwound, the combination of opposite adjustable sup- 70 ports, rotatable coil engaging members mounted on said supports, and means for relatively adjusting the members toward or from each other on said supports to engage and support a coil between them.

In testimony that I claim the foregoing as my own, I affix my signature.

HOWARD B. SHERMAN.
